UNITED STATES PATENT OFFICE

JOSEPH A. KWAKE, OF CHICAGO, ILLINOIS, ASSIGNOR TO CAMEL COMPANY, OF CHICAGO, ILLINOIS, A CORPORATION OF ILLINOIS

LIFT MECHANISM

Application filed October 13, 1932. Serial No. 637,584.

This invention relates to improvements in lift mechanisms.

It is an object of this invention to provide lift mechanisms for sliding doors for railway house cars characterized by greater simplicity of construction, reduction in weight, fewer parts and less fabrication than lift mechanisms of the same general type.

This object, as well as those which will later appear, are attained by the novel structure and combination of parts hereinafter described and more particularly pointed out and defined in the appended claims.

In the accompanying drawings forming part of this specification

Figure 1 is a fragmentary front elevation of a railway house car having a sliding lift door thereon employing a preferred embodiment of the invention, the door being illustrated in lowered position;

Figure 2 is a view similar to Figure 1 showing the door in elevated position;

Figure 3 is a vertical section taken on line 3-3 of Figure 1;

Figure 4 is a horizontal section taken on line 4-4 of Figure 1;

Figures 5 to 8, inclusive, illustrate details of the cams used in the lift mechanism;

Figure 9 is an elevation of an integral operating lever and cam; and

Figure 10 is an end elevation of the structure shown in Figure 9, looking toward the right.

Referring to the preferred embodiment of the invention illustrated in the figures of the drawings, there is shown a door 10 mounted for sliding movement upon a railway house car, the siding 11 and side sill 12 of said car being fragmentarily shown in Figures 1 and 2 of the drawings. The door 10 is illustrated as being formed of metal and provided with a plurality of horizontal corrugations 13 which preferably merge at their opposite ends into vertical corrugations 14 and 15

45 formed in the door adjacent the vertical margins thereof. The horizontal corrugation adjacent the bottom edge of the door is interrupted at spaced points so as to provide relatively flat portions 16 and 17 to which

50 bracket members 18 and 19 are secured. In

its normal or lowered position the door is adapted to be supported upon a track 20 secured to the side sill 12 by means of a plurality of track brackets 21, one of which is shown partially in Figure 3 of the drawings. 55 With reference to this figure of the drawings it will be seen that the lower edge of the door is provided with an angle member 22 and the engagement of the door in its normal position is effected by engagement between the 60 horizontal flange of the angle member and the track. The track 20 takes the form of an angle member positioned with one of its legs 23 extending downwardly for cooperation with upwardly extending flanges 24 provided on the bracket members 18 and 19 to prevent disengagement of the bottom portion of the door from the track. It is to be understood that the structure of the door and of the track are not limited to those shown 65 in the drawings and that the invention may readily be utilized with doors and tracks having structures other than that illustrated. 70

It is contemplated that when it is desired to move the door toward open or closed positions the door be supported upon antifriction means. For this purpose the lift mechanism of the instant invention is utilized. This mechanism embodies an operating lever 25, the lower end of which is formed so as to provide, integral with said lever, a cam portion 26. With particular reference to Figures 9 and 10 of the drawings it will be seen that the cam portion 26 is provided with an integral shouldered stud 27 extending 85 from one side thereof in spaced relation to a similarly extending lug 28. On the opposite side of said cam portion a trunnion 29 is provided. The stud 27 has fastened thereto a cam 30. The cam 30 is slid upon the free end of the stud 27 until it engages the shoulder 31 provided on said cam and fastening of the cam upon the stud is obtained preferably by upsetting the free end of the stud. 90 The cam 30 is maintained upon the stud against rotation relative thereto by engagement with the flat sides 32 and 33 of the stud provided in the formation of the shoulder 31. By this construction the cam 30 is constrained to move with the operating lever. 100

A trunnion 34 is provided upon the cam 30 and in its assembly with the lever 25 extends oppositely from and in alignment with the trunnion 29 provided on the lever. The stud 5 27, as clearly illustrated in Figures 3 and 4 of the drawings, provides an axle for a roller 35 which carries a cage 36 providing a raceway for a plurality of roller bearings 37 mounted within said cage and upon a bushing 38 secured upon the stud. The lever, the cam and the roller are adapted to be pivotally retained upon the door by means of the bracket 19. The trunnion 29 provided on the lever is received for this purpose within a 10 bearing 39 formed in the cover portion 40 of the bracket while the trunnion 34 formed on the cam 30 is received within an aligned bearing 41 formed in the backing portion 42 of the bracket. It is to be observed that the 15 stud 27 upon which the roller 35 is mounted lies in offset relationship to the trunnions 29 and 34.

A somewhat similar lifting mechanism is mounted within the bracket member 18 secured to the door in spaced relation to the bracket member 19. In this mechanism a cam identical with the cam 30 hereinabove described is utilized. This cam is fastened upon a shouldered stud 43 extending integral- 20 ly from a cam 44 in the manner described for the mounting of the cam 30 upon the stud 27 provided on the operating lever. The cam 44 is formed with a lug 45 spaced from and extending in the same direction as the 25 stud 43 and a trunnion 46 extending from the opposite face of the cam. A roller 47 is mounted upon the stud 43 and, as hereinbefore described, is provided with a raceway within which roller bearings are received. 30 The roller bearings are adapted to ride upon a bushing which is mounted on the stud. The assembly of the cams and roller 47 is adapted to be housed within the bracket member 18 with the trunnions provided on the cams jour- 35 naled in corresponding bearings provided in the cover and backing portion of the bracket member.

Inasmuch as the cam 44 is not provided with an operating lever the lift mechanism 40 of which the cam 44 constitutes a part is operated by the lever 25. This operation is ef- 45 fected by means of an actuating bar 48 en- gaged with the cams 26 and 44 by means of the extension of the lugs 28 and 45, respec- 50 tively, through corresponding openings pro- vided adjacent the ends of said bar. The ac- 55 tuating bar 48, as clearly shown in Figure 3 of the drawings, is substantially Z-shaped in section. The lower flange 49 of said bar 60 adjacent the ends thereof is cut away as indicated at 50 and 51 so as to avoid interference with the bracket members 18 and 19 in the 65 operation of the bar.

The operating lever, as appears from Figure 1 of the drawings, extends through an

opening preferably provided in the side of the bracket member 19 and in the normal po- 70 sition of the door extends upwardly in spaced substantially parallel relationship to the door. The upper end of the lever 25 is fashioned to form a hand grip as indicated at 52 and the portions of the horizontal cor- 75 rugations 13 lying in the path of movement of the grip are flattened as indicated at 53 and 54 so as to prevent injury to the hand of the operator. The inner face of the oper- 80 ating lever 25 adjacent the upper end thereof is provided with a spaced projection 55 adapted to engage behind a quadrant 56 se- 85 cured to the door.

Assuming the door to be in its closed po- 90 sition and it is desired to move the door to- 95 ward open position the hand grip of the lever is grasped and the lever depressed from the position shown in Figure 1 of the drawings to that indicated in Figure 2 of the draw- 100 ings. During this movement of the lever the lower end thereof will fulcrum upon the roller 35 and the trunnions 29 and 34 provided, 105 respectively, upon the lower end of the lever and upon the cam 30 will move upwardly and through their engagement with the bracket member 19 fastened to the door will effect elevation of the door. The movement of the operating lever 25 will be transmitted by means of the actuating bar 48 to the cor- 110 115 responding cams journaled in the bracket member 18 whereby these cams will fulcrum upon the roller 47 and through the engage- 120 125 ment between the trunnions 34 and 46 with the bracket member 18 effect elevation of the door. In this position the door is elevated above the track and its weight is supported upon the rollers 35 and 47 so that movement 130 of the door toward open position may be had. This movement may be made easier by grasp- 135 ing the fixed handle 57 provided adjacent the front edge of the door.

It will be apparent that numerous changes and modifications in the details of the pre- 140 145 ferred embodiment of the invention will be apparent to those skilled in the art. It is intended, therefore, that all such changes and modifications be comprehended within this invention, which is to be limited only by the scope of the appended claims.

I claim:

1. In a railway house car, a track, a sliding door normally seated upon said track, in combination with a plurality of spaced rollers resting upon said track; means for mounting each of said rollers upon said door comprising a pair of cams, a stud connecting said cams in spaced relation, a roller mounted upon said stud and spaced bracket members secured to said door, said cams being journaled in said members in offset relationship to said studs, means connecting certain of the cams of each roller, and lever means for

operating one of said cams to elevate said door for support upon said rollers.

2. In combination, a sliding door, a track, said door normally resting upon said track, 5 and means for elevating said door above said track for sliding movement comprising a plurality of rollers engaging said track, a plurality of cams for each roller positioned on opposite sides thereof, a stud extending 10 from one of said cams and secured to the other of said cams, said studs constituting the axles for said rollers, and means comprising trunnions for pivotally mounting said cams upon said door, said trunnions lying in offset relationship to said studs.

3. In a railway house car, a track, a sliding door normally seated upon said track, in combination with a plurality of spaced rollers having rolling engagement with said track, a plurality of cams for each of said rollers, an integral shouldered stud projecting from one of said cams, said studs securing said cams in spaced relation and providing 25 axles for said rollers, means connecting certain of the cams of each roller, means pivotally connecting said cams to said door in offset relationship to said studs and means for operating one of said cams to elevate said door upon said rollers.

4. In a mechanism of the character described, an operating lever, an integral stud extending from said lever adjacent one end thereof, a cam fastened upon said stud in spaced relation to said lever, a roller mounted upon said stud, and means comprising trunnions for pivotally mounting said lever and said cam upon said door, said trunnions being offset relative to said stud.

5. In a lift mechanism for a sliding door, a bracket adapted to be secured to said door, an operating lever, an integral stud extending from said lever adjacent one end thereof, a cam fastened upon said stud in spaced relation to said lever, a roller mounted upon said stud, and means comprising trunnions for pivotally mounting said end of said lever and said cam within said bracket, said trunnions being offset relative to the stud, said lever extending from said bracket in substantially parallel relationship to said door.

6. In a railway house car, a track, a sliding door normally seated upon said track, in combination with a lifting mechanism comprising an operating lever, an integral stud extending from said lever adjacent one end thereof, a cam fastened upon said stud in spaced relation to said lever, a roller mounted upon said stud, means comprising trunnions for pivotally mounting said lever and said cam upon the door, said trunnions

being offset relative to said stud, and a second lifting mechanism mounted upon said door in spaced relation to said first lifting mechanism, said lever being provided with a lug adjacent one end thereof adapted to engage an actuating bar connected to said second lifting mechanism for imparting movement thereto.

7. In a railway house car, a track, a sliding door normally seated upon said track, in combination with a lifting mechanism comprising an operating lever, an integral stud extending from said lever adjacent one end thereof, a cam fastened upon said stud in spaced relation to said lever, a roller mounted upon said stud, means comprising trunnions for pivotally mounting said lever and said cam upon the door, said trunnions being offset relative to said stud, and a second lifting mechanism mounted upon said door in spaced relation to said first lifting mechanism, said lever being provided with a lug adjacent one end thereof adapted to engage an actuating bar, said second lifting mechanism including a cam having a lug engaging said bar.

8. In a railway house car, a track, a sliding door normally seated upon said track, in combination with a plurality of spaced rollers resting upon said track, means for mounting each of said rollers upon said door comprising a pair of cams, a stud connecting said cams in spaced relation, a roller mounted upon said stud and spaced brackets secured to said door, said cams being journaled in said members in offset relation to said studs, means connecting certain of the cams of each roller and lever means having one end positioned in a bracket member for operating one of said cams to elevate said door for support upon said rollers.

9. In a railway house car, a track, a sliding door normally seated upon said track, in combination with a plurality of spaced rollers resting upon said track, means for mounting each of said rollers upon said door comprising a pair of cams, a stud connecting said cams in spaced relation, a roller mounted upon said stud and spaced bracket members secured to said door, said cams being journaled in said members in offset relation to said studs, means connecting certain of the cams of each roller and lever means integral with one of said cams and extending through an opening provided in a bracket member for operating said cam to elevate said door for support upon the rollers.

Signed at Chicago, Illinois, this 28 day of September, 1932.

JOSEPH A. KWAKE.
